UNITED STATES PATENT OFFICE

2,386,160

HEATING APPARATUS

Bernard Goerg, Bronxville, N. Y., assignor to
American Radiator & Standard Sanitary Corporation, New York, N. Y., a corporation of Delaware

Application June 26, 1942, Serial No. 448,552

6 Claims. (Cl. 126—99)

My invention relates to heating apparatus of the type usually employed to heat dwelling houses, and it has for a broad object to provide apparatus of this type which is of improved construction and arrangement of parts and which is simple in design and inexpensive to manufacture.

A further object is to provide a warm air furnace having an improved form of heating unit and an improved and simple means for supporting such unit within the outer furnace casing.

The invention consists in the novel construction and combination of parts, to be more fully described hereinafter, and the novelty of which will be particularly pointed out and distinctly claimed.

In the accompanying drawings, to be taken as a part of this specification, I have fully and clearly illustrated a preferred embodiment of my invention, in which drawings—

Fig. 1 is a vertical sectional view showing one preferred embodiment of my improved heating apparatus, the section being taken on the line 1—1 of Fig. 2;

Fig. 2 is a horizontal sectional view taken on the line 2—2 of Fig. 1; and

Fig. 3 is a perspective view illustrating my improved unitary heating means.

Referring now in detail to the construction illustrated, it is noted that I have shown my invention as embodied in an upright warm air furnace 10 wherein the air to be heated is drawn into the bottom thereof by a fan 11, which fan forces the air upwardly through the furnace and over the external heat-emitting surfaces of a heating means 12 and thence out through the top of the furnace to the space to be heated. It is to be understood at the outside that my invention is not to be considered as being limited to this particular type of heating apparatus, for, in so far as the broader aspects of my invention are concerned, it might equally as well be embodied in other types of heating apparatus.

The furnace 10 comprises a rectangular casing 13 formed by four vertical side panel walls 15, 16, 17 and 18, respectively, formed of sheet metal and extending for the full height of the furnace and joined together at the four vertical corners to form a rigid upright casing structure adapted to be supported by its bottom resting on any suitable support, such as a floor, indicated by the line 19. The lower part of the side panel wall 16 is provided with an opening 20 through which the air to be heated enters the bottom of the casing. A filter 21 which is removably secured within a frame 22 attached to the wall 16, serves to remove

foreign particles from the entering air. A top wall 23, also of sheet metal, joins the upper ends of the walls 15, 16, 17 and 18 and is provided with an outlet opening 24 through which the heated air flows from the casing 13.

The casing is divided horizontally by a wall 25 into a lower air inlet chamber 26 and an upper heating chamber 27. The fan 11 is suitably motor driven and is arranged within the lower chamber 26. The fan has an axial air inlet 28 and a tangential air outlet 29 which discharges the air upwardly through an opening in the division wall 25 and into the heating chamber 27.

Arranged within the heating chamber 27 of the casing is the heating means 12 which is formed as a one-piece structural unit (see Fig. 3). The heating means or unit 12 is here shown as comprising an upright frustro-conical shaped combustion chamber 30 formed of sheet metal and arranged with its smaller end at the top. The heating unit 12 also comprises an annular sheet metal radiator 31 encircling and spaced from the small upper part of the combustion chamber 30 and rigidly joined thereto by a tubular connecting duct 32 formed of sheet metal and suitably welded at its ends to the defining walls of the chamber 30 and radiator 31, respectively. In order to provide a more rigid connection between the combustion chamber and radiator, a vertical brace plate 33 is arranged therebetween and welded along its two vertical edges to the chamber 30 and radiator 31, respectively. The heating unit 12 also comprises an oil burner 34, here shown as being of the vaporizing or pot type. The top of the burner is of substantially the same diameter as the bottom of the combustion chamber and is rigidly secured to and supported by the combustion chamber by means of hanger bolts 35 secured at their upper ends to brackets 36 spot-welded to the chamber 30 and secured at their lower ends to angle pieces 37 extending beneath and supporting the bottom of the burner 34. Air is supplied to the burner 34 through a sheet metal utility duct 38 fixed at its inner end to the burner 34 and extending laterally and outwardly through an opening in the side panel wall 15 of the casing.

As the burner 34 is of a type well known to those skilled in the art, a detail description thereof and of its operation is unnecessary, it being sufficient to say that the flame produced by the burning oil projects upwardly through an opening 39 in the top of the burner and into the combustion chamber 30. The hot combustion gases flow upwardly through the combustion chamber 30 and out of the chamber through the

connecting duct 32 to the radiator 31. A vertical baffle wall 40 within the radiator 31 and adjacent the duct 32 causes the hot gases to flow clockwise (as viewed in Fig. 2) through the radiator to a smoke outlet duct connection 41 extending outwardly from the radiator 31 and through an opening in the upper part of the panel wall 16.

The heating unit 12 is also provided with a utility duct connection 43 which is also formed of sheet metal and extends outwardly from the lower part of the combustion chamber 30 and through an opening in the panel wall 15. The connection 43 serves as a means for observing the operation of the oil burner. Another utility connection is provided by a sheet metal duct 45 extending outwardly from the radiator 31 through an opening in the wall 15. The duct 45 is used as a means for gaining access to the radiator for cleaning the same.

As stated above, the heating means is formed as a one-piece structural unit. A supporting rod 50 extends across the top of the unit 12 and through aligned openings in a pair of rigid supporting elements or hanger plates 51 and 52, respectively, which are located at diametrically opposite sides of the heating unit and are suitably welded to the outer defining walls of the radiator. The two ends 53 and 54 of the rod 50 provide rigid supporting elements for the unit 12 and extend outwardly from opposite sides of the radiator 31 to opposite corners of the casing 13. The two ends 53 and 54 extend through vertical slots 56 provided in bracket devices 57 and 58, respectively, the latter being suitably welded to the walls 17 and 18, respectively. As shown in Fig. 2, the rod 50 is threaded at its ends and is fixed with respect to the hanger plates by means of clamping nuts 60 threaded on the rod and engaging the outer faces of hanger plates 51 and 52, respectively. The end 53 is fixed to the bracket device 57 by means of a pair of clamping nuts 62 and 63 threaded on the end 53 and engaging opposite sides of the part of the bracket 57 carrying the slot 56. Likewise, the end 54 is fixed to the bracket device 58 by means of a pair of clamping nuts 64 and 65 threaded on the rod and engaging opposite sides of the part of the bracket 58 in which the vertical slot 56 is formed.

The rod 50 and brackets 57 and 58 provide a simple and effective means for suspending the heating unit 12 from the casing 13. The slots 56 in the brackets 57 and 58 and the clamping nuts 62, 63, 64 and 65 provide a means for adjusting vertically either end of the rod with respect to the casing 13 so as to properly level or position the heating means within the casing 13. The utility connections 38, 41, 43 and 45 are attached to the casing walls by means of screws 70 extending through the walls and through radial flanges 71 formed as a part of rings 72 which are spot-welded, respectively, to the several utility connections. The weight of the unit 12 is carried by the rod 50 and brackets 57 and 58, the connections 38, 41, 43 and 45 with their rings 72 screwed to the casing walls provide a means of steadyng the unit and preventing sideways displacement thereof. It will be noted that the rod 50 substantially intersects the vertical axis of the unit 12 at a substantial distance above the center of mass thereof.

In addition to the advantages of simplicity and of low cost of the construction described and to the improved and inexpensive means for supporting the heating unit, a further advantage

is that because the combustion chamber is frusto-conical in shape, the diameter of the radiator may be kept small for a given heat capacity of furnace without restricting the required flow spaces for the air to be heated which are between the radiator and the combustion chamber and between the radiator and outer casing, respectively.

What I claim and desire to secure by Letters 10 Patent of the United States is:

1. Heating apparatus comprising an upright casing of rectangular horizontal section adapted to be supported at its bottom and having an inlet for air to be heated and an outlet for the heated air, heating means arranged within said casing and comprising a fuel-burning part and a heat-emitting part joined together to form a one-piece structural unit, a pair of bracket devices fixed, respectively, to diagonally opposite

15 corners of said casing at the upper end thereof, a pair of rigid supporting elements secured, respectively, to the upper part of said structural unit and extending radially outwardly from opposite sides thereof towards said casing, and means 20 for fixing the outer parts of said elements to said bracket devices for vertical adjustment thereon, respectively, so as to suspend said unit from said casing.

2. Heating apparatus comprising an upright 25 casing adapted to be supported at its bottom and having an inlet for air to be heated and an outlet for the heated air, heating means arranged within said casing and comprising a fuel-burning part and a heat-emitting part joined together to form a one-piece structural unit, a pair of bracket devices fixed, respectively, to opposite sides of said casing at the upper end thereof, each of said devices having a vertical

30 slot open at the top, a single supporting rod 35 fixed to said structural unit and extending across the top of said unit from one side thereof to the other side and having its two ends extending outwardly and beyond said unit from opposite sides thereof and toward said casing to provide a pair of rigid supporting elements, and means for adjustably fixing the outer parts of the two ends 40 of said rod within the slots of the two bracket devices, respectively, so as to suspend said unit at a desired height in and from said casing.

3. Heating apparatus comprising an upright 45 casing adapted to be supported at its bottom and having an inlet for air to be heated and an outlet for the heated air, heating means arranged within said casing and comprising a fuel-burning part and a heat-emitting part joined together to form a one-piece structural unit, a pair of bracket devices fixed, respectively, to opposite sides of said casing at the upper end thereof, a pair of rigid supporting elements secured, respectively, to the upper part of said structural

50 unit and extending upwardly from opposite sides thereof, and a rod extending through the tops of said elements and into said bracket devices, respectively, and including means for adjusting the height of each of said supporting elements with respect to its respective bracket device, whereby 55 the unit is suspended from its top within said casing and the unit may be properly positioned within said casing.

4. Heating apparatus comprising an upright 60 casing adapted to be supported at its bottom and having an inlet for air to be heated and an outlet for the heated air, heating means arranged within said casing and comprising a fuel-burning part and a heat-emitting part joined together

to form a one-piece structural unit, a pair of bracket devices fixed, respectively, to the upper part of said casing and at opposite sides of the latter and each of said bracket devices being provided with a slot extending generally in an upward and downward direction, a rod-like supporting element secured to the upper part of said structural unit with its axis extending across and above the center of mass of the unit and extending outwardly from opposite sides thereof and towards said casing and the outer end portions of said elements being arranged, respectively, within said slots, and means for securing said elements to said devices at a desired level within said slots whereby said structural unit is suspended from the upper part of said casing and said unit may be properly positioned within said casing.

5. Heating apparatus comprising an upright casing adapted to be supported at its bottom and having an inlet for air to be heated and an outlet for the heated air, heating means arranged within said casing and comprising a fuel-burning part and a heat-emitting part joined together to form a one-piece structural unit, a pair of bracket devices fixed, respectively, to the upper part of said casing and at opposite sides of the latter and each of said bracket devices being provided with a slot extending generally in an upward and downward direction, a rod-like supporting element secured to the upper part of said structural unit with its axis extending transversely across and above the center of mass of the unit and extending outwardly from opposite sides thereof and towards said casing and the outer end por-

tions of said elements being arranged, respectively, within said slots, said elements being threaded and each provided with two nuts for engaging the opposite faces of the cooperating slotted brackets, whereby the elements may be secured at any desired level in the slots and the structural unit may be adjusted laterally for centering in the casing from the upper part of which it is suspended.

- 10 6. Heating apparatus comprising an upright, rectangular casing adapted to be supported at its bottom and having an inlet for air to be heated and an outlet for the heated air, heating means arranged within and spaced from all walls of said casing and comprising a fuel burning part and a heat emitting part joined together to form a one-piece structural unit having its maximum transverse dimension at the top, a pair of hanger plates extending upwardly from the unit and spaced in accordance with said dimension and having aligned perforations, a bracket secured to each of opposite walls of the casing near diagonally opposite corners thereof, each bracket having an arm which is vertical and extends across the adjacent corner, each arm having an open topped vertical slot, a rod for supporting said unit from said casing and extending through said perforations and slots, means to position the hanger plates on the rod, means to position the rod longitudinally in the slots, said last mentioned means also adjustably securing the rod ends vertically in said slots whereby the unit can be centered and plumbed in the casing.
